UNITED STATES PATENT OFFICE.

GEORGE H. GARDINER, OF NEW YORK, N. Y., ASSIGNOR, BY MESNE ASSIGNMENTS, TO
WICHERT & GARDINER, A CORPORATION OF NEW YORK.

SHOE.

1,163,522.

Specification of Letters Patent. Patented Dec. 7, 1915.

Application filed July 1, 1912, Serial No. 706,924. Renewed April 24, 1914. Serial No. 834,221.

To all whom it may concern:

Be it known that I, GEORGE H. GARDINER, a citizen of the United States, residing in New York, borough of Brooklyn, in the 5 State of New York, have invented certain new and useful Improvements in Shoes, of which the following is a specification.

This invention relates to improvements in shoes and more particularly to pumps, and 10 has for its object to provide an improved shoe or pump in which the heel is attached to the body of the shoe in a secure manner.

The object of the invention is also to provide a construction which will enable the 15 high or French heel to be successfully used on the class of shoes known as pumps.

To this end the invention comprises the insertion in the shank of the pump of a metallic stay which is vertically flexible and 20 transversely stiff and the peculiar connection of the stay, outer sole, and heel as hereinafter claimed. This construction serves to brace the foot against laterally turning and prevents the heel from being broken off 25 from the body of the shoe.

The invention is shown in the accompanying drawings, will be described more fully hereinafter, and will be finally pointed out in the claims.

30 In the accompanying drawings, Figure 1 is a side view partially in longitudinal section of a lady's shoe or pump, having a French heel, and showing a stay secured in place, Fig. 2 is a top view partially broken away, and with the heel and stay indicated in dotted lines, Fig. 3 is a side elevation similar to Fig. 1, but showing the stay employed with a shoe, the heel-seat of which does not extend forward of the heel, and 40 Fig. 4 is a perspective view of the stay.

Similar references indicate corresponding parts in the different drawings.

The heel 10 is secured to the heel-seat 11 in any suitable manner, as for example, by cement; and the breast 12 of the heel is faced 45 with the extended rear portion of the outer sole 13, which thereby conceals the rear portion 14 of the stay, the forward portion 15 of which is received between the insole 16 and the portion 17 at the shank of the shoe. 50

The stay is preferably made of spring

steel of uniform thickness and tension throughout, and it is flexible in vertical direction so as to permit the necessary flexibility of the shoe at the shank, but said heel-stay is transversely stiff and substantially non-yielding. To secure this vertical flexibility and transverse rigidity and to adapt the stay without change to various sizes and shapes of shoes, the stay consists of a narrow elongated strip 15 of spring steel adapted to fit any shoe shank and provided at its rear end with a broadened downward extension 14 which engages the breast of the heel. 60 The elongated strip is provided with screw holes disposed apart longitudinally and the downward extension is provided with screw holes disposed apart laterally. The stay is of general arc-shape to conform to the shank of the shoe in its normal condition. The 70 stay is secured to the breast of the heel by screws 18 which pass through the holes in the downward extension 14 into the body of the heel and the stay is seated in a recess 75

At its forward portion 15 the stay is secured to the portion 17, and is also secured to the inner side of the outer sole 13, by means of rivets 19, or by any other suitable means, such as nails, stitches or cement sufficient to secure the forward portion of the stay in place relatively to the shank of the shoe, so that the outer sole and heel-seat are connected to receive and withstand lateral and twisting strains, communicated to the 80 stay.

The heel-seat 11 may be extended as shown in Fig. 1 so as to form practically an intermediate sole throughout the shoe, or it may be terminated at any point desired, 90 as it is not necessary that the heel-seat extend forward of the heel. Such a construction is shown in Fig. 3, in which the heel-seat 20 extends only over the heel. In this case the stay does not pass through the heel-seat, but the forward portion 15 of the stay is located between the insole 16 and the outer sole 13 of the shoe. In this case, the stay is fixed at its forward portion 15 by rivets 19 to the inner part of the outer 95 sole 13.

For providing a broad bearing of the stay

upon the heel and thereby permitting wide spacing of the screws 18 or other securing means, and thereby attaining the better bracing resulting from such attachment at 5 wide lateral separated points on the heel; the rear portion 14 of the heel-stay is made wider than the forward portion 15 as clearly shown in Fig. 4 and indicated in dotted lines in Fig. 2, whereby this better bracing effect 10 is attained without increasing the vertical stiffness of the stay in its forward portion. If the stay were made the full width of the part 14 over its entire length, it might be too stiff at that portion in the shank of the shoe, 15 and the desired flexibility could then be attained only by other means, as for instance, thinning the metal. By enlarging the rear end, the necessary bracing and the proper flexibility of the forward portion are obtained in a stay made of metal of uniform 20 thickness.

It is obvious that the shoe to which the stay is applied may consist of elements at the shank other than those which have been 25 shown in the drawings, and in such case the stay may be secured between any of these elements provided the same coöperative law herein set forth is maintained.

The invention is not limited to the particular form of stay shown, nor to this particular arrangement described, as changes may be made therein without departing from the spirit of the invention as defined by the appended claims, and as other embodiments of the invention may be used.

I claim:

1. A boot or shoe, having an outer sole and heel, a vertically-flexible transversely-stiff arcuate heel-stay shaped to adjacent 40 portions of the breast of the heel and shank of the shoe, and secured at its front end to the outer sole at the inner side thereof, and extending outwardly from the inner part of the outer sole and toward the heel at its 45 other end, and secured at said end to the breast of the heel, the said stay being intermediate the heel and sole.

2. A boot or shoe comprising a heel, a heel-seat provided with a forward extension 50 projecting in front of said heel, a stay secured to said forward extension of the heel-seat and provided with a downward extension secured to the breast of the heel, and an outer sole having a downward extension 55 secured to the breast of the heel and covering said downward extension of the stay and having its inner part secured to the free end of the stay, the said stay being arranged intermediate the heel and inner part of the 60 outer sole.

3. In a boot or shoe, the combination of an outer sole, a heel, and a vertically-yieldable transversely-stiff stay secured at one end to the rearward part of the outer sole at

the inner side thereof, and at the other end 65 to the breast of the heel, the said stay being intermediate the breast of the heel and sole, the outer sole extending over the stay and to the heel.

4. In a boot or shoe, the combination of a 70 heel, an outer sole extending to the heel, and a stay secured at one end to the outer sole, with one side adjacent thereto and at the inner side thereof, and at the other end to the breast of the heel, with the other side of 75 the stay adjacent thereto, the said stay being intermediate the heel and sole.

5. An improved boot or shoe, comprising a heel, an outer sole, said outer sole extending over the breast of the heel, said heel 80 having a recessed portion, and a stay secured to the inner part of the outer sole having one portion secured to the breast of the heel at the recessed portion and a front portion secured to the inner part of the outer 85 sole.

6. An improved boot or shoe, comprising a heel having a recessed portion, an outer sole, and a stay having one part thereof engaging the recessed portion and the front 90 part thereof secured to the inner part of the outer sole, said outer sole extending over the stay at the heel-portion and over the recessed portion of the heel.

7. An improved boot or shoe, comprising a 95 heel having a recessed portion in the breast of the heel, a stay secured therein and flush with the surface of the heel, and an outer sole having its inner part secured to the forward part of the stay and extending over 100 the heel-portion of the stay and the recessed portion of the heel.

8. In a boot or shoe, the combination of a heel, an outer sole, and a stay secured at one end to the outer sole with one side adjacent 105 thereto and at the inner side thereof, and at the other end to the breast of the heel with the other side of the stay adjacent thereto, the said stay being intermediate the heel and sole, and the said stay having a broadened 110 portion at that portion thereof seated on the heel.

9. In a boot or shoe, the combination of a heel having a recessed portion at the breast thereof, an outer sole extending to the heel, 115 and a stay having a broadened portion seated in the recess of the breast of the heel and secured thereto at the broadened end, and a forwardly-extending narrower portion secured at one end to the outer sole, with one 120 side adjacent thereto and at the inner side thereof, the said stay being intermediate the heel and sole.

10. The combination, with a heel, the outer sole extending to the heel, and an insole or 125 shank piece, of a vertically flexible, transversely stiff stay between the outer sole and insole or shank piece, the outer sole, and the

forward end of the insole or shank piece and the stay being riveted together, and extending along the arch portion to the heel, and forming a spring support between the sole and heel, and secured to the breast of the heel.

In testimony, that I claim the foregoing

as my invention, I have signed my name in presence of two subscribing witnesses.

GEORGE H. GARDINER.
